CARRYING FRAMES IN ACCOUNTING MACHINES

Angus G. Helgeson, Birmingham, Mich., assignor to The National Cash Register Company, Dayton, Ohio, a corporation of Maryland

Application June 14, 1950, Serial No. 168,029

12 Claims. (Cl. 101—96)

1

This invention relates to accounting machines and similar business machines, and is directed particularly to the recording means of such types of machines.

The invention is embodied in machines of the general type shown in the following United States Letters Patents, and reference may be had to them for a complete showing and description of standard mechanisms not disclosed herein; United States Patents Nos. 1,619,796; 1,747,397; and 1,761,542, issued March 1, 1927, February 18, 1930, and June 3, 1930, respectively, to Bernis M. Shipley; No. 2,175,346, issued October 10, 1939, to Maximilian M. Goldberg; No. 2,141,332, issued December 27, 1938, to Charles H. Arnold; No. 1,693,279, issued November 27, 1928, to Walter J. Kreider; and No. 2,361,662, issued October 31, 1944, to Pascal Spurlino and Konrad Rauch.

More particularly, the invention relates to insertable carrying frames for listing tapes of the general type shown in the above mentioned Spurlino and Rauch Patent No. 2,361,662.

Machines of this particular type, and embodying the present invention are well adapted for use in banks, and especially in the proof departments thereof, where the various items are listed and distributed, and deposits checked for proof balance at the end of each day.

The insertable carrying frames for the listing tapes, as illustrated in the above mentioned Spurlino and Rauch patent are provided, each with a single listing tape and impression means cooperating with that tape, whereas in the present invention each of the insertable carrying frames is provided with a plurality of listing tapes and a plurality of impression means cooperating with those tapes.

Since many banks require their lists of checks or items paid by another bank to be accompanied by a printed list of checks paid by a bank, when these checks are sent back to the banks on which they are drawn, the present invention with the plurality of listing tapes in each of the insertable frames provides the proof departments with a large number of individual tapes upon which the individual lists of groups of items may be printed without having to increase the number of sets of type wheels now on the machine.

Therefore, in use in connection with these and other requirements of the banks, a machine which prints individual lists of groups of items, along with other identification data on deposit slips which may be imprinted in connection with the machine of the Spurlino and Rauch type, and the totals of the distributed items, is not

2

only a great time-saver for the employees of the bank, but also provides accurate machine-printed results immediately at the close of the day's business, and with the plurality of tapes in each of the insertable frames, the efficiency of the department is greatly increased in that they can handle many more groups of checks from many more banks than has been done in the past.

It is, therefore, one object of this invention to provide an accounting machine with means for distributing items into a plurality of classifications, and also to provide a plurality of insertable listing tape frames, each frame being provided with a plurality of listing tapes or detail strips for recording the items of such classifications.

Another object is to provide means for selecting one of said tapes of each of the frames to receive the printed data from an item, said selection being controlled by the selection of the classification totalizer, which receives said item.

A further object is to provide a plurality of impression means carried by each of said insertable frames, each of the impression means being associated with one of the individual listing tapes or detail strips of its respective removable frame.

Another object of the present invention is to provide a common actuating or operating means for the plurality of impression means of each of the insertable frames.

Another object of the present invention is to provide a feeding device for each of the plurality of listing tapes or detail strips in each of the insertable frames, which feeding mechanism is operated selectively, according to the impression means which has been selected to record upon the selected tape.

Another object of the present invention is to provide a plurality of impression means for the plurality of listing tapes in each of the insertable tape carrying frames, said impression means being of the squeeze impression type.

A still further object of the present invention is to provide a modified form of impression means associated with each of the listing tapes or detail strips in the insertable frame.

A still further object of the present invention is to provide a novel feeding means for each of the tapes, which feeding means is actuated by the means which operates the impression means for the tapes.

With these and other incidental objects in view the invention includes certain novel features of construction and combination of parts, the essential elements of which are set forth in appended

claims, and a preferred and modified form of embodiment of which is hereinafter described with reference to the drawings which accompany and form a part of this specification.

In said drawings:

Fig. 1 is a side elevation of the insertable tape carrying frame with the right side frame thereof removed, except for a small portion shown at the upper and righthand corner, and shows the relative locations of the two listing tapes or detail strips, the impression means therefor, and the feeding means for said tapes.

Fig. 2 is a sectional view of a portion of the machine taken to the right of a transaction bank, showing the two lower keys in this bank and also the differential mechanism associated with this bank of keys, and the drive from the differential to set up the impression control selecting means.

Fig. 3 is a front elevation of the insertable tape carrying frame, showing the relative positions of the two listing tapes.

Fig. 4 illustrates the impression rolls for the two listing tapes and the selecting means for the impression rolls, and the mechanism for actuating the front roll.

Fig. 5 is a similar view showing the mechanism for selecting and actuating the rear impression roll.

Fig. 6 is a detail view showing the means for lifting the impression rolls into position to be rolled over the type to make the impressions therefrom, and also illustrates the selecting feeler shaft operating means.

Fig. 7 is a detail view showing the front impression roll in the position it assumes after printing and at the end of the forward stroke of the operating cams, and in a position ready to cause the detail strip to be fed; this view also shows in detail the tape feeding mechanism for both the upper and lower tapes.

Fig. 8 is a similar view showing the rear impression roll in a position after printing and at the end of the forward stroke.

Figs. 9 to 13 show modified forms of a different type of impression means for the two listing tapes.

Fig. 9 is a side elevation taken just inside the right side frame, and shows the relative positions of the impression means and the different locations of the listing tapes, the parts all being in their normal positions.

Fig. 10 is a detail view showing the means for selecting and operating the rear hammer.

Fig. 11 is a similar view showing the means for selecting and operating the front hammer.

Fig. 12 is a detail view showing the rear hammer in position to take an impression from the type wheels, this view also showing the feeding mechanism for both the upper and lower listing tapes.

Fig. 13 is a similar view showing the front hammer in position to take an impression from the type wheels.

GENERAL DESCRIPTION

Described in general terms, the present invention embodies an insertable tape carrying frame, carrying a plurality of listing tapes adapted to be used in a machine of the type shown in the above mentioned Spurlino and Rauch Patent No. 2,361,662, for the purpose of making detail records of checks as they are run through the machines in the proof departments of banks, whereby these tape lists may be torn from the

tape carrying frame and sent back to the respective banks, along with the checks that have come from those banks.

The invention involves a plurality of impression means, one for each of the listing tapes, with means for selecting one of the impression means for each operation of the machine, such means being under the control of transaction keys which control the differential mechanism, 10 which in turn operates hammer selecting mechanism similar to that disclosed in the above mentioned Spurlino and Rauch patent.

After each of the tapes has been printed upon there is provided a feeding mechanism which is 15 operated to feed the tape. In other words, only the tape is fed which is printed upon during any one operation of the machine.

In the operation of the present invention the impression mechanism is selected by the depression 20 of one of two transaction keys and after the selection has been made a camming device is operated to raise the impression mechanism into a position whereby the selected impression roll may be rolled over the type to take the impression 25 on the listing tape, which is passed beneath the type wheels and above the impression means.

The listing tape of the upper tape supply roll 30 is fed from the supply roll around a front impression roll, downwardly around an idler roll and thence between feed rolls from whence it is fed outwardly so as to be easily torn off, to be 35 attached to the batch of checks. The tape from the rear supply roll is fed upwardly over an impression roll associated with this tape and downwardly around an idler roll and thence between feed rolls from whence it may be torn from the roll, to likewise be attached to certain batches of checks.

DETAILED DESCRIPTION

Control keys and differential mechanism

In Fig. 2 there is shown a portion of a transaction or control bank of keys and the differential mechanism associated therewith, which in turn, 45 under control of the keys, actuates means to control the selection of the impression means for one or the other of the two listing tapes or detail strips.

Two control keys 61 and 62 are mounted in 50 the usual key frame 63 supported by the usual rods 64 (only one of which is shown).

Pivoted around the usual tie rod 65 is a differentially adjustable arm 66. Pivoted at 67 to the arm 66 is a latch 68 having a foot which lies 55 above a shoulder 69 of a driver 70 also pivoted around the tie rod 65. Pivoted at 71 to the differential arm 66 is a bell crank 72, the upper end of which is connected to the latch 68 by a link 73. A spring 74 connected to the bell crank 72 normally holds the foot of the latch 68 above the shoulder 69 on the driver 70.

The driver 70 is given a clockwise movement and then a counterclockwise movement each operation of the machine by the following means:

Pivoted on the stationary stud 80 is a lever 81 carrying rollers 82 and 83, cooperating with cams 84 and 85 which are secured to a main drive shaft 86 of the machine. A link 87 connects the upper end of the lever 81 and the driver 70.

As the shaft 86 rotates in a clockwise direction the lever 81 is rocked first clockwise and then counterclockwise, which through the link 87 rocks the driver 70 first clockwise and then counterclockwise to its normal position.

Upon the clockwise movement of the driver

70 the latch 68 and differential arm 66 are carried upwardly until a nose 88 of the bell crank 72 strikes the inner end of a depressed key 61 or 62, as the case may be. When this occurs the continued movement of the driver 70 causes the bell crank 72 to be rocked counterclockwise, and the link 73 withdraws the foot of the latch 68 from the driver 70 whereupon the main surface of the foot then rides on a surface 89 of the driver 70 during the remainder of the clockwise movement of the driver 70. Thus, the differential arm 66 is stopped in a position depending upon whichever one of the keys 61 or 62 is depressed.

The differential arm 66 is locked in such differentially set position by means of a nose 90 of the link 73 engaging an appropriate notch 91 of a plate 92 which is secured to the key frame 63.

Upon return movement of the driver 70 in a counterclockwise direction, a surface 93 thereof contacts a stud 94 of the differential arm 66 and restores the differential arm to its normal position. As the shoulder 69 of the driver 70 passes below the foot of the latch 68, the spring 74 rocks the latch 68 clockwise so as to again put it above the shoulder 69 of the driver 70.

As the lever 81 nears the end of its clockwise movement, a roller 95 contacts a surface 96 of a usual minimum-movement beam 97 pivoted to the differential arm 66. The right end of this beam has a slot 98 engaging a stud 99 of a link 100, the lower end of which is pivoted to an arm 101 pivoted on the shaft 102. As the lever 81 completes its clockwise movement, the contact of the roller 95 with the surface 96 of the beam forces the beam 97 against a rub 102 and insures that the link 100 will be set differentially in accordance with the position of the differential arm 66 under control of the keys 61 or 62 which have been depressed.

The arm 101 is secured to a segment 103 which meshes with an idler gear 104 which in turn meshes with a pinion 105, which turns on a shaft 106.

This pinion 106 is secured to two plates 107 and 108. The plate 107 has a notch 109 and the plate 108 has a notch 110 for the purpose of controlling the selection of the impression means in a manner to be hereinafter described.

Removable tape carrying frame

As has been previously pointed out the removable tape carrying frame involved in the present invention is particularly adapted to be used in a machine of the type disclosed in the Spurlino and Rauch Patent No. 2,361,662.

This removable frame is adapted to be inserted into a machine of the type shown in the last mentioned Spurlino and Rauch patent to have recorded on the plurality of tapes, in this removable carrying frame, data with reference to checks from various banks, as those checks are run through the proof departments of banks, and the amounts thereof are recorded in the accounting machine shown in the above mentioned patent.

The removable tape carrying frame is composed of a lefthand plate 121 and a righthand plate 122 (Figs. 1 and 3) having flanges 123 and 124, respectively, and studs 125 and 126, respectively. These flanges 123 and 124 and the pins 125 and 126 are used to guide the removable tape carrying frame when it is inserted in the machine, such as is shown in the above mentioned

Spurlino and Rauch Patent No. 2,361,662. Two side plates 121 and 122 are held together the proper distance apart by tie rods 127, 128, 129, and 130, as shown in Fig. 1.

5 As has been previously stated, this removable tape carrying frame carries two listing tapes or detail strips.

The upper listing tape or detail strip 135 is fed from a supply roll 136 over a roller 137 mounted to turn freely on the tie rod 128, and then over an impression roll or platen 138 mounted to turn freely on a rod 139 supported by a pair of rockable plates 140 and 141.

The rockable plates 140 and 141 are mounted 15 to oscillate on a rod 142 carried by a swinging frame composed of a pair of plates 143 and 144 secured together by a rod 145 and mounted to pivot on the tie rod 128.

From the platen 138 the listing tape is passed 20 downwardly beneath a roller 150, mounted to turn on a rod 151 carried by the rockable plates 140 and 141. The strip is then fed over an idler roll 152 mounted on the tie rod 129 and thence over an idler roll 153 on the tie rod 127 and 25 and then forwardly over a knurled feeding roller 154 mounted on a rod 155 carried by the side plates 121 and 122.

The knurled roll 154 is caused to move step by step in a counterclockwise direction, by means 30 to be hereinafter described, whereupon the leading end of the listing tape 135 is, due to the fact that it is held against the roller 154 by a tension roller 156, fed between a plate 159 and a tear-off bar 160, both of which are secured to 35 the side plates 121 and 122. The means for operating the impression roll or platen 138 and also the tape feeding mechanism will be hereinafter described.

The supply roll 136 is provided with the usual 40 core 165 by means of which said roll 136 is mounted on two short studs 166 and 167 (Fig. 3). The stud 166 is carried by a bracket 168 secured to the side plate 121. The stud 167 is carried by a bracket 169 secured to the side plate 122.

45 This bracket 169 is made of springy metal and has a finger 170 to facilitate in mounting the supply roll on the studs 166 and 167. When it is desired to put in a new supply roll 136 the operator takes hold of the finger 170 and springs 50 the bracket 169 toward the right (Fig. 3) a distance sufficient to insert a supply roll 136 in between the brackets 168 and 169 and cause it to be set over the studs 166 and 167 whereupon the operator releases the finger 170 and the 55 bracket 169 will then spring back into the position shown in Fig. 3.

The lower listing tape or detail strip 175 is fed from a supply roll 176 (Figs. 1 and 3) upwardly past an idler roll 177 carried by the 60 rod 145, and thence over an impression roll or platen 178 mounted to turn freely on a rod 179 carried by the rockable plates 140 and 141. From the platen 178 the strip is fed downwardly over a roller 180 mounted to turn freely on a rod 181 also supported by the rockable plates 140 and 141. From the roller 180 the strip is then fed 65 over an idler roll 182 mounted on the tie rod 130. From the idler roll 182 the strip is led forwardly over a knurled feeding roller 184 mounted on a rod 185 carried by the side plates 121 and 122. A tension roller 186 carried by a lever 187 pivoted on a rod 188 carried by the side plates 121 and 122 is held by a spring 189 against the top 70 of the listing tape 175, so that when the knurled

roller 184 is rotated step by step in a counter-clockwise direction, by means to be hereinafter described, the tape 175 will be fed to the left between a plate 190 and a tear-off bar 191 carried by the plates 121 and 122.

The lower listing tape supply roll 176 is provided with the usual core 195 which is mounted upon short studs 196 and 197 (Figs. 1 and 3). The stud 196 is carried by a bracket 198 secured to the side plate 121 and the stud 197 is carried by a bracket 199 secured to the side plate 122. The bracket 199 is made of springy metal and has a finger 200 to facilitate inserting the supply roll 176 between the two brackets 198 and 199 by simply taking hold of a finger 200 on the bracket 199 and moving it toward the right as viewed in Fig. 3, whereupon the supply roll 176 may be inserted between the brackets 198 and 199 onto the studs 196 and 197.

The platens 138 and 178 are selected for operation by the two keys 61 and 62 in the manner to be hereinafter described, whereupon they may be rolled over the type wheels to take an impression on the tapes 135 and 175, respectively from their associated type wheels, which are indicated at 201 in Figs. 1 and 4 to 8. The usual inking ribbon 202 is provided to make the records on the tapes 135 and 175 legible.

Impression operating means

To take an impression from the type 201 by means of the impression roll or platen 138, the swinging frame consisting of the plates 143 and 144 is rocked counterclockwise about the rod 128 to raise the platen 138, after which the plates 140 and 141 are rocked clockwise as a unit, whereupon the platen 138 contacts the bottom of the type 201, and as the plates 140 and 141 continue to rock clockwise, the platen 138 is rolled over the ribbon 202 and type 201, thus taking an impression from the type wheels onto the listing tape 135.

Immediately after the platen 138 has passed the type wheel, the swinging frame, consisting of the plates 143 and 144 is immediately lowered, whereupon the plates 140 and 141 are rocked counterclockwise back to the position shown in Fig. 1.

In Fig. 6 the platen 138 is shown in the position in which it is taking an impression, through the ribbon 202, from the type wheels 201 on the listing tape 135, and in Fig. 7 the parts are shown in the position immediately after the impression has been made, with the swinging frame 143—144 having been moved clockwise into its normal lower position, after which the plates 140 and 141 are rocked counterclockwise to their normal positions.

In Fig. 4 there is shown a pair of cams 210 and 211 secured to a printer drive shaft 213 carried by the machine frames. This printer drive shaft 213 receives its motion from the main operating shaft 86 (Fig. 2) in a manner to be hereinafter described.

The cams 210 and 211 cooperate with rollers 214 and 215 respectively mounted on a bell crank 216 secured to a shaft 217, also carried by the machine frames. Also secured to the shaft 217 is an arm 218 to which is pivoted a link 219. The left end of the link 219 has a notch 220 normally in the position shown in Fig. 4, but which is adapted to engage a pin 221, by means to be hereinafter described, on an arm 222 of an impression operating slide 223 mounted to slide on a bar 224 secured to the side plate 121. The

slide 223 carries a stud 225 projecting into a slot 226 of the plate 140.

When the left end of the link 219 has been lowered so that the notch 220 engages the pin 221, the cams 210 and 211 rock the bell crank 216 counterclockwise whereupon the slide 223 is moved to the left (Fig. 4) into the position shown in Fig. 7.

As has been previously stated, just prior to the time the platen 138 reaches the type wheels 201 it is raised by the swinging frame 143—144 so that when the plate 140 has been rocked clockwise by the slide 223 as just described, the platen 138 would then be in the position shown in Fig. 6 wherein it will roll over the type 201 and take an impression from the type on the listing tape 135. As soon as this impression is made the swinging frame 143—144 is lowered after which the cams 210 and 211 rock the bell crank 216 clockwise to its normal position whereupon the link 219 restores the slide 223 to the right to the position shown in Fig. 4, thus rocking the plates 140 and 141 back to the position shown in Fig. 4.

A guide plate 227 (Figs. 1, 7 and 8) is secured to the plate 121, and a guide lug 228 is secured to the bar 224 to guide the slide 223 in its forward and backward movements.

The means for rocking the swinging frame, consisting of the plates 143 and 144 will now be described. Secured to the printer drive shaft 213 is a disk cam 231 (Figs. 4 and 6) cooperating with a roller 232 on an arm 233, pivoted on a stud 234 on the machine frame. A spring 235 holds the roller 232 against the cam surface 231. The left end of the arm 233 is provided with a slot 236 to surround a rod 237 carried by the plates 143 and 144 of the swinging frame. The cam 231, swinging frame 143—144 and arm 233 are in their normal positions, shown in Fig. 4.

As the shaft 213 rotates clockwise the cam 231 gradually rocks the arm 233 clockwise until it assumes the position shown in Fig. 6 whereupon the roller 232 is adjacent the high part of the cam 231.

In this position, as has been previously stated, the platen 138 is rolled over the type wheels 201 to take the impression on the tape 135 and immediately thereafter, and upon continued movement of the cam 231 in a clockwise direction the roller 232 drops off the high portion of the cam under the tension of the spring 235 to immediately rock the swinging frame 143—144 in a clockwise direction from the position shown in Fig. 6 to that shown in Fig. 4.

The means for driving the shaft 213 consists of the following mechanism shown in Fig. 2. In axial alignment with the main cam shaft 86 is a shaft 241, which has secured thereto a gear 242, meshing with an idler gear 243 mounted on a stud 244 on the machine frame. The gear 243 meshes with a gear 245 secured to the printer cam shaft 213.

By means of a clutch device not shown herein, but which is fully illustrated and described in the United States Letters Patent No. 2,467,704, issued to Pascal Spurlino, Rudolph Moser, Alfred Kibler, Marvin Frost, and Walter Kreider, the clockwise movement of the main drive shaft 86 is communicated to the gear 242 and shaft 241, whereupon through the idler gear 243 and gear 245 the shaft 213 is driven one clockwise rotation simultaneously with the clockwise rotation of the main operating shaft 86 during all adding operations and also during the second cycle of total and sub-total operations.

During the first cycle of each total and sub-total operation the clutch device disconnects the shaft 241 from the shaft 86 so that the printer mechanism will not be operated during such first cycles of the total and sub-total operations, as has been fully illustrated and described in the last mentioned Spurlino et al. Patent No. 2,467,704.

To cause the platen 178 to take an impression on the listing tape 175, the slide 223 is moved from its normal position, shown in Fig. 4, to the right, to the position shown in Fig. 8, by means which will now be described.

Referring particularly to Figs. 5 and 8, there is secured to the printer cam shaft 213 another pair of cams 250 and 251, which cooperate with rollers 252 and 253 of a bell crank 254 secured to the shaft 217. Also secured to this shaft 217 is an arm 255 to which is pivoted a link 256, the left end of which has a notch 257 adapted to be moved downwardly into engagement with the previously described pin 221 on the arm 222 of the platen operating slide 223.

In Fig. 8 the link 256 has been moved downwardly by means to be hereinafter described, and when in such position and upon clockwise movement of the shaft 213, the cams 250 and 251 rock the bell crank 254 clockwise, whereupon the slide 223 is moved from the position shown in Fig. 5 toward the right to the position shown in Fig. 8, and its stud 225, through its engagement with the plate 140 rocks the plate 140 and the plate 141 counterclockwise, thus moving the platen 178 from the position shown in Fig. 5 to that shown in Fig. 8.

The above described cam 231 moves the platen 178 upwardly against the type wheel 201 as has been described in connection with the platen 138, so that as the plates 140 and 141 complete their counterclockwise movement, the platen 178 will roll over the type wheels and take an impression therefrom upon the listing tape 175. After the impression is taken the swinging frame 143-144 is lowered again by the spring 235 when the roller 232 drops off the high part of the cam 231 in the same manner as in connection with the platen 138, after which the cams 250 and 251 rock the bell crank 254 counterclockwise, thus moving the impression operating slide 223 to the left from the position shown in Fig. 8 into its normal position, shown in Figs. 1 and 5.

Impression Platen Selecting Means

Whether the platen 178 or the platen 138 is to be operated is dependent upon the coupling of the link 256 with the pin 221 or the link 219 with the pin 221 which in turn is controlled by the keys 61 and 62.

Whenever the key 61 is depressed, the previously described disk 107 is moved from the position shown in Fig. 5 to the position shown in Fig. 8, whereupon a feeling finger 261 is shown engaged with the notch 109 of the disk 107. This feeling finger 261 is pivoted to an arm 262, pivoted on a shaft 263 carried by the printer frame. This arm 262 is drawn by a spring 264 so that it normally contacts a pin 265 of an arm 266 which is secured to the shaft 263. Pivoted to the arm 262 is a link 267 which is also pivoted to the link 256.

In Fig. 5 the feeling finger 261, the arm 266, arm 262, and link 267 are shown in their normal positions. During the operation of the machine, the shaft 263 is rocked in a counterclockwise direction by means of a pair of cams 270 and 271, cooperating with rollers 272 and 273 of a bell

crank 274, pivoted on the shaft 217. The bell crank 274 is connected by a link 275 to an arm 276, which is secured to the shaft 263. The cams 270 and 271 cause the shaft 263 to be rocked 5 counterclockwise and then clockwise to normal position.

When the shaft 263 is rocked counterclockwise the arm 266 is rocked likewise, and if the disk 107 has been moved into a position where the notch 109 is opposite the feeling finger 261, by the operation of the differential mechanism shown in Fig. 2 under control of the key 61, then the finger 261 will enter the notch 109 and consequently the arm 262 can be rocked counterclockwise by its spring 264 a distance sufficient to cause the link 267 to lower the link 256 and cause the notch 257 to engage the pin 221 on the arm 222 of the impression actuating slide 223 so that the slide will be operated by the cams 250 and 251 in the manner previously described, to cause an impression to be made from the type 201 by the platen 178 to print on the listing tape 175.

The disk 108 is adapted to be set under the control of the key 62 and when this key is depressed and the differential mechanism of Fig. 2 moves the disk 108 so that the notch 110 is opposite a feeler finger 281 (Figs. 4 and 7) on an arm 282 pivoted on the shaft 263. The arm 282 is normally held by a spring 284 against a stud 285 of an arm 286 secured to the shaft 263. The arm 282 is connected by a link 287 to the previously described link 219.

When the shaft 263 is rocked counter-clockwise in the manner previously described, and the notch 110 is opposite the feeler finger 281, the spring 284 rocks the arm 282 counterclockwise a distance sufficient to cause the notch 220 of the link 219 to engage the pin 221 so that when the cams 210 and 211 operate to move the link 219 first to the left and then to the right in the manner previously described, the slide 223 will be moved likewise to cause the impression roller 138 to take the impression from the type wheels 201 on the listing tape 135.

Strip Feeding Mechanism

As earlier mentioned, there is associated with the listing tape 135 a feeding mechanism to advance the tape after each impression thereon from the type wheels 201 by the impression roll 138. Likewise there is a separate feeding mechanism associated with the listing tape 175, to advance this tape one step after each impression thereon from the type wheels 201 by the platen roll 178.

The feeding mechanisms for both tapes 135 and 175 is operated partially by the platen operating slide 223. The feeding mechanism for the upper listing tape or detail strip 135 will be described first. Secured to the side of the feed roller 154 is a ratchet 291 (Figs. 1 and 7). Pivot-60 ed on the rod 155 adjacent the ratchet 291 is an arm 292, carrying a pawl 293, held by a torsion spring 294 in engagement with the ratchet 291. A spring 295 holds the arm 292 normally in the position shown in Fig. 1, wherein it contacts the plate 227, which acts as a stop for the arm 292.

When the impression operating slide 223 is moved from the position shown in Fig. 1 to the position shown in Fig. 7 a roller 296 carried by the slide 223 engages the arm 292 and rocks the arm clockwise from the position shown in Fig. 1 into the position shown in Fig. 7, which is sufficient to move the feeding pawl 293 backwardly

11

slightly over one tooth space so that it engages the next lower adjacent tooth of the ratchet 291. A stationary pin 297 carried by the side plate 121 acts as a limiting stop for the clockwise movement of the arm 292.

This clockwise movement of the arm 292 puts the spring 295 under tension, and when the slide 223 is restored to the right to its normal position and the roller 296 is released or moved away from the arm 292, the spring 295 rocks the arm 292 counterclockwise, whereupon the feeding pawl 293 turns the ratchet 291 one tooth space, which in turn rotates the feeding roller 184 one step to advance or feed the listing tape 135 so that the leading end of the tape is fed further past the cut-off bar 160.

During the time the arm 292 is rocked clockwise and the pawl 293 pulled downwardly over the ratchet teeth and to prevent any retrograde movement of the ratchet 291, and consequently of the feed roll 184, a retaining pawl 298 is held in engagement with the ratchet 291 by a torsion spring 299. This retaining pawl 298 is pivoted on a block 300 (Fig. 7) which is secured to the left side 121 of the removable tape carrying frame.

The means for feeding the lower listing tape 175 will now be described. Secured to the side of the feeding roller 184 (Figs. 1, 7 and 8) is a ratchet 311. Mounted on the rod 185, adjacent the ratchet 311 is an arm 312, carrying a feed pawl 313, held in engagement with the ratchet 311 by a torsion spring 314. A spring 315 holds the arm 312 normally against a stop pin 316 carried by the side plate 121.

When the impression operating slide 223 is moved from its normal position in Fig. 1 into its righthand position, as shown in Fig. 8, to cause an impression to be made by the impression roller 178 from the type 201, a block 317 secured to the slide 223 contacts the upper part of the pawl-carrying arm 312 and rocks said arm from the position shown in Figs. 1 and 7 into the position shown in Fig. 8, until said arm comes against a stationary stop pin 318 carried by the side plate 121. This movement of the arm 312 is sufficient to raise the pawl 313 up slightly over one tooth space on the ratchet 311 so that when the slide 223 is returned to the left from the position shown in Fig. 8 into that shown in Fig. 1, and the block 317 leaves the arm 312, the spring 315 rocks said arm 312 in a counterclockwise direction whereupon the pawl 313 turns the ratchet 311 and consequently the feeding roller 184 one step to advance the lower listing tape or detail strip 175 beyond the cut-off or tear-off bar 191.

During the time the arm 312 is being rocked in a clockwise direction a retaining pawl 319 held by a torsion spring 320, in engagement with the ratchet 311, prevents any retrograde or clockwise movement of the ratchet 311, and consequently of the feed roller 184. The retaining pawl 319 is mounted on a block 321, carried by the left side plate 121.

MODIFIED FORM

Modified removable tape carrying frame

In Figs. 9 to 13 inclusive there is illustrated a modified form of removably tape-carrying frame, with modified forms of mechanisms for feeding the tapes, taking impressions on the tapes from the type wheels, and for mounting the tapes.

This removable tape carrying frame is composed of a lefthand plate 340 and a righthand plate 341 (Figs. 9 and 12) having flanges 342 and

12

343, respectively, and studs 344 (only one of which is shown). The flanges and the studs are used to guide the removable tape-carrying frame when it is inserted in the machine, such as is shown in the above mentioned Spurlino and Rauch Patent No. 2,361,662. The plates 340 and 341 are held together, the proper distance apart, by tie rods 345, 346, 347, 348, 349, 350, 351 and 352, all of which are shown in Fig. 9.

This modified removable tape-carrying frame carries two listing tapes or detail strips. The upper listing tape or detail strip 355 is fed from a supply roll 356 over an idler roller 357 carried by a rod 358 which acts as a tie rod for a pair of arms 359 and 360 pivoted on the tie rod 348. From the roller 357 the strip 355 is fed over a roller 361 carried by a rod 362 and thence over a roller 363 carried by a rod 364 and then upwardly over a printing platen 365, then over a roller 366 carried by the tie rod 345 and then forwardly between a flexible feed roller 367 and the supply roll 356, which is held by means to be hereinafter described, constantly against the leading end of the tape 355 as it is passed between the roller 367 and the supply roller 356. The roller 367 is mounted to turn on a rod 368 carried by the frames 340 and 341.

The above described rods 362 and 364 act as tie rods for and are carried by a pair of oscillating plates 370 (Fig. 9) and 371 (Fig. 10), which are mounted to oscillate as a unit on the tie rod 345 by means to be hereinafter described. The platen 365 is carried in a channel bar 372, supported by the plates 370 and 371.

The feed roller 367 is caused to move step by step in a clockwise direction, by means to be hereinafter described, whereby the leading end of the tape 355 is, due to the fact that it is held between the roller 367 and the supply roll 356 by torsion springs 374 only one of which is shown. One spring 374 is wrapped around the rod 348 and has one end attached to the bottom of the arm 359 and the other end attached to the frame plate 341. The other spring 374, which is not shown is wrapped around the rod 348 and has one end attached to the bottom of the arm 360 and the other end attached to the frame plate 340. The leading end of the tape 355 is fed between a plate 375 and a tear-off bar 376 supported by the plates 340 and 341.

By means to be hereinafter described, the oscillating plates 370 and 371, which form a platen operating frame for the platen 365 will be moved counter-clockwise to force the platen 365 and tape 355 against a ribbon 202 to take an impression from the type wheels 201.

The supply roll 356 is mounted on a rod 377, which in turn is mounted to turn in half-round bearings 378 of the previously described arms 359 and 360.

As above stated, the springs 374 (only one of which is shown), by their constant pressure cause the arms 359 and 360 to be forced in a clockwise direction, and consequently hold the outer diameter of the supply roll 356 in constant engagement with the leading end of the tape 355 so as to press it against the feed roll 367, whereby, upon turning the feed roll 367 in a clockwise direction, the leading end of the tape 355 is fed outwardly between the plate 375 and the tear-off bar 376.

The fact that the supply roll 356 is constantly diminishing in size makes no difference to the feeding because the arms 359 and 360 are always moved or pressed in a clockwise direction and

therefore its outer periphery will always contact the leading end of the strip and hold it in firm engagement against the feed roller 367.

The lower listing tape 385 is fed from a supply roll 386 up over an idler roll 387 mounted on a rod 388 supported by the frame plates 340 and 341. From the roll 387 the tape is fed over a roller 389 mounted on a rod 390 and from there over a roll 391 mounted on a rod 392, and thence upwardly over a printing platen 395, over a roller 396 mounted on the rod 346 and thence over a roller 397 on the rod 347. From the roller 397 the tape is fed downwardly between the supply roll 386 and a roller 398 on the rod 352, and then between the supply roll 386 and the stud 351. From here the tape 385 is fed upwardly over a roller 400 carried by a stud 401, which connects a pair of arms 402 and 403, which arms are pivoted on the tie rod 343, previously described. The leading end of the tape 385 is then passed between knurled feed rollers 404 and 405. The roller 404 is mounted on a rod 406 carried by the plates 340 and 341, and the roller 405, which is a tension roller, is carried by an arm 407 pivoted on a stud 408 carried by the side plate 341. This tension roller 405 is held by a spring 409 in contact with the tape or detail strip 385 pressing it against the feed roller 404. After passing between the rolls 404 and 405 the end of the tape 385 is passed downwardly over a plate 410 and under a tear-off bar 411, both of which are secured to the side plates 340 and 341.

The above described rods 390 and 392, which support the idle rolls 389 and 391, are carried by a pair of oscillating plates 420 (Fig. 9) and 421 (Fig. 10) which, by the means of these two studs 390 and 392 are formed into a frame to support the printing platen 395, which in turn is carried by a channel bar 422, also supported by the plates 420 and 421.

The lower listing tape supply roll 386 rests upon the roller 398 and the tie rod 351, and is held in such a position by the arms 402 and 403, which have half-round bearings 423, which engage a shaft 424 projecting from each end of the supply roll 386. Torsion springs 425 (only one of which is shown) are wrapped around the rod 349 adjacent the arms 402 and 403. Each spring 425 has one end against its respective arm 402 or 403, and the other end of the spring being held firmly against the plate 341 and 340, respectively, to always apply a clockwise movement to the arms 402 and 403, thereby holding the supply roller 386 firmly against the roller 398 and rod 351, even as the supply roll 386 diminishes in size.

The platens 365 and 395 are selected for operation by the two keys 61 and 62 in a manner to be hereinafter described, whereby said platens are moved to press their respective tapes 355 and 385 against the ribbon 202 to take a legible impression from the type wheels 201.

Impression operating means

The means for rocking the frame consisting of the plates 370 and 371 to move the platen 365 against the ribbon 202 to take an impression on the upper listing tape or detail strip 355 will now be described.

Secured to the operating shaft 213 is a pair of cams 430 and 431 (Figs. 11 and 13) which cooperate with rollers 432 and 433, respectively, of a bell crank 434 secured to the shaft 217. Also secured to the shaft 217 is an arm 435, having pivoted thereto a link 436, the left end

of which is provided with a notch 437 adapted to be moved into engagement with a pin 438 on a platen frame operating slide 439.

The slide 439 has a slot 440 into which projects a stud 441, carried by the side plate 340. A collar 442 holds the lower end of the slide 439 in its proper lateral position.

The slide 439 is adapted to be moved horizontally back and forth and to prevent any rocking of the slide its upper edge 443 lies just below the two previously described tie rods 345 and 346. This slide 439 lies next to the side plate 340 on the inside thereof, and just back of the two oscillating plates 371 and 421.

The plate 439 is provided with an operating pin 444, projecting past the edge of the oscillating plate 371 (Fig. 10). When the left end of the link 436 has been moved downwardly from the position shown in Fig. 11 into the position shown in Fig. 13, the notch 437 is in engagement with the pin 438. The means for moving this link 436 downwardly will be hereinafter described.

With the notch 437 engaging the pin 438, upon clockwise movement of the shaft 213, the cams 430 and 431 rock the bell crank 432, shaft 217, and arm 435 clockwise, whereupon the link is moved to the right, thus moving the slide 439 to the right from the position shown in Fig. 11 into the position shown in Fig. 13. Upon such movement of the slide 439, the pin 444, by its engagement with the oscillating plate 371 rocks the plate 371 and its associated plate 370 counterclockwise to move the platen 365 from the position shown in Figs. 10 and 11 into the position shown in Fig. 13, to cause a legible printed impression to be made on the upper tape or detail strip 355, from the type wheels 201. Immediately after the impression has been made the cams 430 and 431 restore the bell crank 434 and arms 435 to their normal positions, thus moving the slide 439 from the position shown in Fig. 13 to the left, back into position shown in Figs. 10 and 11, whereupon, as the stud 444 is moved to the left the platen frame consisting of the oscillating plates 370 and 371 is rocked clockwise by gravity back into the position shown in Figs. 9, 10 and 11.

To print upon the lower tape or detail strip 385 the plates 420 and 421 are rocked clockwise from the position shown in Figs. 9, 10 and 11, into the position shown in Fig. 12 by the following mechanism:

Secured to the cam shaft 213 is a pair of cams 445 and 446 (Figs. 10 and 12), which cooperate with rollers 447 and 448 of a bell crank 449 secured to the shaft 217. Also secured to the shaft 217 is an arm 450 having pivoted thereto a link 451, the left end of which has a notch 452 adapted, by means to be hereinafter described, to be moved into engagement with the pin 438 on the hammer operating slide 439. The slide 439 also has an operating stud 453 which projects past and is adapted to cooperate with the right-hand edge of the platen supporting plate 421 (Fig. 10).

When the notch 452 of the link 451 has been engaged with a pin 438 and the shaft 213 rotates in a clockwise direction, the cams 445 and 446 rock the bell crank 449, shaft 217, and arm 450 in a counterclockwise direction whereupon the link 451 moves the slide 439 to the left from the position shown in Figs. 9, 10 and 11, into the position shown in Fig. 12, whereupon the operating pin 453 rocks the platen frame consisting of the

plates 420 and 421 clockwise, to move the platen 395 against the type wheels 201 to take an impression on the lower detail strip 385 through the ribbon 202. After the impression has been made, the slide 439 upon continued movement of the cams 445 and 446, is moved back into the position shown in Fig. 10, whereupon the plates 420 and 421 rock clockwise, as the pin 453 is moved to the right, so that the platen 395 is restored by gravity to its normal position.

Platen selecting means

Whether the platen 365 or the platen 395 is to be operated is dependent upon the coupling of the links 436 and 451 with the pin 438, which in turn is controlled by the keys 61 and 62 (Fig. 2).

Whenever the key 61 is depressed, a disk 460 (Fig. 11) is moved from the position shown in this figure into the position shown in Fig. 13 by the previously described differential mechanism and train of gears shown in Fig. 2. When the disk 460 is in the position shown in Fig. 13, a feeling finger 461 is moved into engagement with a notch 462 of the disk 460. This feeling finger 461 is pivoted to an arm 463, which in turn is pivoted on the shaft 263, and is held by a spring 464 in contact with a stud 465 on an arm 466 which is secured to the shaft 263. Pivoted to the arm 463 is a link 467, which is also pivoted to the link 436.

In Fig. 11 the feeling finger 461, the arm 463, arm 466, and link 467 are shown in their normal positions. During the operation of the machine the shaft 263 is rocked in a counterclockwise direction and then clockwise, back to normal position by means of the cams 270 and 271 (Fig. 5) previously described.

When the shaft 263 is rocked counterclockwise the arm 466 is rocked likewise, and if the disk 460 has been moved into a position where the notch 462 is opposite the feeling finger 461, as shown in Fig. 13, by the operation of the differential mechanism shown in Fig. 2 under control of the key 61, then the finger 461 will enter the notch 462 and consequently the arm 463 can be rocked counterclockwise, by its spring 464, to follow the stud 465 to cause the link 467 to lower the link 436 and cause the notch 437 to engage the pin 438 on the slide 439 so that the slide will be operated, in the manner previously described, by the cams 430 and 431, to cause an impression to be made from the type wheels 201 by the platen 365, to print on the listing tape or detail strip 355.

To select the platen 395 for printing, the key 62 (Fig. 2) is depressed, whereupon, under the control of the differential mechanism and train of gears shown in Fig. 2, a disk 470 (Figs. 10 and 12) is moved from the position shown in Fig. 10 into the position shown in Fig. 12, whereupon a feeling finger 471 is moved into a notch 472 of the disk 470. The feeling finger 471 is pivoted on an arm 473, in turn pivoted on the shaft 263, and held in engagement by a spring 474, with a stud 475 on the arm 476, which is secured to the shaft 263.

During the operation of the machine, the shaft 263 is moved first counterclockwise and then clockwise by the cams 270 and 271 (Fig. 5) in the manner previously described, whereupon the feeling finger 471 is moved from the position shown in Fig. 10 into the position shown in Fig. 12, due to the fact that the spring 474 causes the arm 473 to follow the stud 475, which is moved counterclockwise with the shaft 263. Pivoted to

the arm 473 is a link 477, which is also pivoted to the link 451. When the arm 473 is moved counterclockwise in the manner above described, when the finger 471 engages the notch 472 of the cam 470, the link 477 lowers the left end of the link 451 and causes the notch 452 to engage the stud 438 of the hammer operating slide 439 and consequently upon movement of this slide by the cams 445 and 446, the platen 395 is moved into printing position to cause this platen 395 to take an impression from the type wheels 201 onto the lower listing tape or detail strip 385.

Strip or tape feeding mechanism

There is associated with the listing tape 355 a feeding mechanism to advance the tape step by step for each printing operation, the timing of the feeding being such that the tape is advanced just prior to the printing thereon by the platen 365.

There is also a feeding mechanism associated with and adapted to operate the lower listing tape 385, which feeding mechanism is operated so as to feed this tape step by step each operation of the machine just before the printing thereon is made by the platen 395.

The feeding mechanism for the upper tape 355 will be described first. Secured to the feed roll 367 (Fig. 9) is a ratchet 481 (Fig. 12), which is engaged by a spring-pressed feed pawl 482, carried by an arm 483, pivoted on the rod 368. A pin 484 carried by the arm 483 is normally held in engagement with a surface 485 of the platen operating slide 439 by a spring 486 attached to an arm 487 which is integral with the arm 483. In Figs. 9 and 12 the arm 483 and pin 484 are shown in their normal positions.

When the slide 439 is moved to the right in the manner previously described, to take an impression from the type wheels by the platen 365, the pin 484 is caused to ride down a cam surface 488 on the slide 439 by the action of the spring 486. At the same time the pawl 482, being carried by the arm 483, turns the ratchet 481 one step in a clockwise direction to feed the strip or tape 355 just prior to the time the platen 365 strikes the type 201.

At the end of the movement of the slide 439 to the right, the pin 484 is at the bottom of the cam surface 488 and the pawl 482 is in the position shown in Fig. 13, whereupon the feeding of the strip 355 has been completed.

Now, as the platen operating slide 439 is moved to the left from the position shown in Fig. 13 into its normal position shown in Figs. 9 and 12, the cam surface 488 in cooperation with the pin 484 rocks the arm 483 counterclockwise whereupon the pawl 482 is moved upwardly a distance slightly greater than one tooth space on the ratchet 481 to get it into position for the next feeding operation.

In order to prevent any rectograde movement of the ratchet 481 and consequently the feed roll 367 while the arm 483 is being restored and the pawl 482 lifted, there is provided a spring-pressed retaining pawl 490 which is carried by the side plate 340.

The means for feeding the lower listing tape 385 just prior to the printing thereon by the platen 395 will now be described. Secured to the feed roller 404 is a ratchet 491 (Figs. 12 and 13). Engaging this ratchet is a spring-pressed feeding pawl 492, carried by an arm 493, pivoted on the rod 406. This arm 493 and consequently the pawl 492 are held in their normal positions

by a spring 494, which holds the arm 493 against a stationary pin 495 carried by the side plate 340.

When the platen operating slide 439 is moved from its normal position, shown in Fig. 9, into its lefthand position, shown in Fig. 12, to cause an impression to be made from the type wheels 281 by the platen 395, a surface 496 of the slide 439 contacts the upper righthand edge of the arm 493 and rocks said arm counterclockwise from the position shown in Fig. 13 into the position shown in Fig. 12, whereupon the pawl 492 turns the ratchet 491 and feed roller 404 counterclockwise one step of movement to feed the lower listing tape or detail strip 385 to the left. This movement of the arm 493 takes place just prior to the time the platen 395 strikes the type 281.

After the printing has taken place the slide 439 is moved toward the right as previously described, whereupon the spring 494 rocks the arm 493 clockwise back to the position shown in Fig. 13, in contact with the stop pin 495 and at the same time raises the pawl 492 slightly more than one tooth so as to be ready for the next feeding motion.

In order to prevent any clockwise movement of the ratchet 491 and feed roller 404 during this restoring movement of the arm 493, a retaining pawl 497 carried by a stationary block 498 secured to the plate 340 is held in engagement with the ratchet 491.

While the forms of mechanism herein shown and described are admirably adapted to fulfill the objects primarily stated, it is to be understood that it is not intended to confine the invention to the exact forms of embodiment herein disclosed.

What is claimed is:

1. In a machine of the class described, the combination of an insertable record strip carrier having parallel side walls and connecting means therefor; a plurality of record strips carried by said carrier; a plurality of record strip feeding means carried by said carrier; a plurality of impression means carried by said carrier between said walls; actuating means mounted in said carrier and common to the plurality of impression means to actuate said impression means; a plurality of operating means mounted in the machine and outside said carrier to operate said common actuating means; a plurality of selectively operable coupling means mounted in the machine and outside of said carrier; selectively operable means to operate said plurality of coupling means to selectively couple said operating means with said common actuating means when said carrier is inserted in the machine, to cause said common actuating means to actuate one of said impression means to print on one of said record strips, and to cause operation of the record strip feeding means associated with said one record strip; and manipulative means to determine which of said selectively operable means shall be operated.

2. In a machine of the class described, the combination of an insertable record strip carrier including side walls connected by tie members; a plurality of record strips carried by said carrier; a plurality of impression means carried by said carrier within said walls; actuating means mounted within the carrier and common to all of said impression means to actuate said impression means; a plurality of operating means

mounted in the machine and outside the carrier walls to operate said common actuating means; a plurality of selectively operable coupling means mounted in the machine and outside said carrier

5 walls; selective means to operate the coupling means to selectively couple said operating means with said common actuating means when said carrier is inserted in the machine, to cause said common actuating means to actuate one of said impression means to print on one of said record strips; and manipulative means to determine which of said selective means shall be operated.

3. In a machine of the class described, the combination of an insertable record strip carrier 15 comprised of side walls and tie members therefor; a plurality of record strips carried by said carrier; a plurality of record strip feeding means carried by said carrier; a plurality of impression means carried by said carrier within said side walls; actuating means common to all of said impression means, said actuating means being carried within the walls of said carrier; a plurality of means carried by said common actuating means to cause operation of said record strip 20 feeding means; a plurality of operating means mounted in the machine and outside of said carrier walls to operate said common actuating means, said operating means being normally disconnected from said actuating means; selectively 25 operable coupling devices mounted in the machine and outside of said carrier; selectively controlled means to operate the coupling devices to selectively connect said operating means with said common actuating means when said carrier is inserted in the machine to cause said actuating means to selectively actuate said impression means to selectively print on said record strips; and manipulative devices to control the selective 30 of said selectively controlled means.

4. In a machine of the class described, the combination of an insertable record strip carrier; a plurality of record strips carried by said carrier; a plurality of record strip feeding means carried by said carrier, a plurality of impression means carried by said carrier; a member carried by said carrier and common to all of said impression means and adapted to selectively 45 actuate said impression means; a plurality of devices carried by said member to cause selective operation of said record strip feeding means

50 upon operation of said member; a plurality of operating means mounted in the machine to operate said member, said operating means being normally disconnected from said member; a coupling device mounted in the machine; means to 55 operate said coupling device to connect one of said operating means with said member to move said member in one direction to actuate one of said impression means to print on one of said record strips and cause operation of one of said record strip feeding means; another coupling device mounted in the machine; means to operate the latter coupling device to connect another of said operating means to said member to move said member in another direction

60 to actuate another of said impression means to print on another of said record strips and cause operation of another of said record strip feeding means; and means to select which of said coupling operating means shall be operated.

5. In a machine of the class described, the combination of an insertable record strip carrier; a plurality of record strips carried by said carrier; a plurality of record strip feeding means carried by said carrier; a plurality of impression means

sion means; rockable means carrying said impression means, said rockable means being carried by said insertable record strip carrier; a member carried by said record strip carrier and adapted, when said carrier is inserted in the machine, to be moved in one direction to operate said rockable means to move one of said impression means into impression-taking position to print on one of said record strips, and cause operation of one of said record strip feeding means, said member adapted to be moved in another direction to operate said rockable means to move another of said impression means into impression-taking position to print on another of said record strips and cause operation of another of said record strip feeding means; a link and cam device to move said member in said one direction; and a second link and cam device to move said member in said another direction.

6. In a machine of the class described, the combination of an insertable record strip carrier; a plurality of record strips carried by said carrier; a plurality of impression means; rockable means carrying said impression means, said rockable means being carried by said insertable record strip carrier; a member carried by said record strip carrier and adapted, when said carrier is inserted in the machine, to be moved in one direction to operate said rockable means to move one of said impression means into impression-taking position to print on one of said record strips, said member adapted to be moved in another direction to operate said rockable means to move another of said impression means into impression-taking position to print on another of said record strips; and a plurality of selectable members mounted in the machine to actuate said rockable means.

7. In a machine of the class described, the combination of an insertable record strip carrier; a plurality of record strips carried by said carrier; a plurality of record strip feeding means carried by said carrier; a plurality of impression means; rockable means carrying said impression means, said rockable means being carried by said insertable record strip carrier; a member carried by said record strip carrier and adapted when said carrier is inserted in the machine, to be moved in one direction to operate said rockable means to move one of said impression means into impression-taking position and cause operation of one of said record strip feeding means, said member adapted to be moved in another direction to operate said rockable means to move another of said impression means into impression-taking position and cause operation of another of said record strip feeding means; and selectively operable means mounted in the machine to determine the direction of movement of said member.

8. In a machine of the class described, the combination of an insertable record strip carrier; a plurality of record strips carried by said carrier; a plurality of record strip feeding means carried by said carrier; a plurality of impression means; rockable means carrying said impression means, said rockable means being carried by said insertable record strip carrier; a member carried by said record strip carrier and adapted, when said carrier is inserted in the machine, to be moved in one direction to operate said rockable means to move one of said impression means into impression-taking position, said member adapted to be moved in another direc-

tion to operate said rockable means to move another of said impression means into impression-taking position; means carried by said member to cause operation of one of said record strip feeding means when said member is moved in one direction; and means carried by said member to cause operation of another one of said record strip feeding means when said member is moved in said another direction.

10. 9. In a machine of the class described, the combination of an insertable record strip carrier; a plurality of record strips carried by said carrier; a plurality of impression means; rockable means carrying said impression means; a rockable frame carrying said rockable means, said frame being carried by said insertable record strip carrier; a member carried by said record strip carrier and adapted, when said carrier is inserted in the machine, to be moved in one direction to operate said rockable means to move one of said impression means into impression-taking position to print on one of said record strips, said member also adapted to be moved in another direction to operate said rockable means to move another of said impression means into impression-taking position to print on another of said record strips; and means mounted in the machine to rock said rockable frame when said rockable means is being rocked by any of the movements of said member; and means mounted in the machine to operate said member.

10. In a machine of the class described, the combination of an insertable record strip carrier; a record strip carried by said carrier; record strip feeding means for said strip, said feeding means being carried by said carrier; an impression means for said record strip; a second record strip carried by said carrier; a record strip feeding means for said second record strip, said feeding means being carried by said carrier; an impression means for said second strip; a rockable member common to both of said impression means and supporting the same, said rockable means being carried by said carrier; a slidable member carried by said carrier; means mounted in the machine to move the slidable member in one direction to rock said rockable means in one direction, to move said first mentioned impression means into printing position to effect printing on the first mentioned record strip, when said carrier is inserted in the machine; a device on said slidable member to cause operation of said first mentioned feeding means when said member is moved in said one direction; means mounted in the machine to move the slidable member in another direction, to move said second mentioned impression means into printing position to effect printing on said second mentioned record strip; and a device on said slidable member to cause operation of said second mentioned feeding means when said member is moved in said another direction.

11. In a machine of the class described, the combination of an insertable record strip carrier; a plurality of record strips carried by said carrier; a plurality of rockable impression means carried by said carrier; a slidable device adapted, when said carrier is inserted into the machine, to be moved in two directions, said member being carried by said carrier; a member carried by said device to engage and rock one of said impression means when said device is moved in one direction to print on one of said record strips; and a second member carried by said device to engage and rock another of said impression

means when said device is moved in another direction to print on another of said record strips; and selectively operable devices mounted in the machine to actuate said slideable device in both directions.

12. In a machine of the class described, the combination of an insertable record strip carrier; a plurality of record strips carried by said carrier; a plurality of record strip feeding means carried by said carrier, a plurality of rockable 10 impression means carried by said carrier; a slideable device adapted, when said carrier is inserted into the machine, to be moved in two directions, said member being carried by said carrier; a member carried by said device to engage and 15 rock one of said impression means when said device is moved in one direction; a second member carried by said device to engage and rock said another of said impression means when said device is moved in another direction, means on 20

said device to cause operation of said one-strip feeding means when said device is moved in said one direction; and means on said device to operate another of said strip feeding means when 5 said device is moved in said another direction.

ANGUS G. HELGESON.
